UNITED STATES PATENT OFFICE.

JOSHUA A. SHAW, OF GILLESPIE, ILLINOIS.

SELF-CHECKING CORN-PLANTER.

SPECIFICATION forming part of Letters Patent No. 329,091, dated October 27, 1885.

Application filed July 23, 1885. Serial No. 172,368. (No model.)

To all whom it may concern:

Be it known that I, JOSHUA A. SHAW, a citizen of the United States, residing at Gillespie, in the State of Illinois, have invented 55 certain new and useful Improvements in Self-Checking Corn-Planters, of which the following is a specification, reference being had herein to the accompanying drawings.

Figure 1 is a plan or top view of the improved self-checking corn-planter, showing one of the marking and checking devices elevated out of operation. Fig. 2 is a section taken longitudinally and vertically through the machine, on one side of the center thereof, 15 as indicated by the dotted line $\alpha\alpha$ on Fig. 1. Fig. 3 is a front view and section in detail through one of the corn-boxes, showing one of the marking and checking devices and the indicator.

20 This invention relates to certain improvements on self-checking corn-planters, which will be fully understood from the following description, when taken in connection with the annexed drawings.

25 The main frame A of the machine is mounted on two transporting-wheels, B B', the latter one of which turns loosely on its axle B², and the other is fast on this axle. On axle B² are two toothed clutching-hubs, C C'. The hub 30 C is fast on its axle, and the hub C' is loose thereon, except when engaged with the hub C. The hub C' is constructed with a cam-shaped groove, a, a ratchet-surface, a', and a grooved collar, a², and it is held in gear with hub C by a helical spring, b.

D designates a hand-lever, which is pivoted to an arm or standard of the frame A, so that it can be vibrated laterally for the purpose of disengaging hub C' from hub C when it is desired to stop dropping. This hand-lever can also be vibrated longitudinally, and to a lateral extension of it a spring-actuated pawl, c, is applied, connected by a rod, c', to an angular hand-grasp, c². By means of this pawl 45 the attendant can actuate the seed-slide when the machine is stationary, thereby enabling him to adjust the dropping at any time to the position of a "check," so that the corn can always be dropped in the proper hill, either 50 in starting the machine at the end of a row or at any other point.

E designates a laterally-vibrating lever, which has its fulcrum at the middle of the length of a cross-bar fixed to the beams of frame A. The rear end of this lever enters 55 the cam-groove a in the hub C', and receives vibration therefrom when the machine is moved forward, and this hub is in gear with the hub C. The front end of the lever E is longitudinally slotted at d, and passes freely 60 through a slot in connecting-block d' of the two seed-slides e e, which slot d receives a pin vertically through it. The vibrating movements of the lever E thus impart a rectilinear reciprocating motion to the two seed-dropping 65 slides. The slides e e work through two corn-boxes, F F, which are secured upon the ends of the beam G of the runner-frame H, to which the runners or drill-openers are secured. The runner-frame, its runners H', the seed-boxes, 70 and seed-guides may be constructed in the usual well-known manner, and provided with a rigid draft-tongue, I, and this frame is hinged at h to the main frame A. The lever used for depressing and raising the runner-frame is preferably arranged on the side thereof. 75 To the extensions G' of the beam G arms J are connected by pivots g, so that the markers J', which are secured to the outer ends of said arms, can accommodate themselves freely to 80 the undulations of the surface of the ground, and also so that either one or both of the arms J can be turned up against the corn-boxes. To the heels of the markers J', I attach the pointed checkers K by pivots k, so that they can 85 be vibrated crosswise of the impressions made by the markers and caused to leave well-defined checks in the surface of the ground, indicating exactly where the hills should be. The upper arms of the checkers K have end- 90 wise movable rods l linked to them, which are guided by eyes fixed into the rear sides of the arms J, and to the inner ends of the rods l rods m are linked, which are detachably connected by hooks to a cross-piece, n, rigidly 95 secured to the lever E just in rear of its front slotted end. Each marker-arm is sustained against backward strain, when depressed, by a front brace-rod, p, linked to the front cross-beam of the runner-frame, and each marker-arm is provided with a rope or chain, r, passed through a pulley-standard, s, on a corn-box, 100

and extended back to the driver's seat for the purpose of raising a marker out of operation. Only one marker is used at a time, and the machine is provided with two, to save time and labor of changing a single marker from one side of the machine to the other at the ends of the rows. At the middle of the length of the beam G, and to the rear edge thereof, I secure a pointed indicator, L, which is in sight to the driver when on his seat, and which serves to direct him how to guide the machine, so that the dropping will always be at the checks. The said indicator should always point to the lines in the earth made by the marker and to the checks made by the checker.

It will be observed that the same motion that drops the corn works the checkers.

Having described my invention, what I claim, and desire to secure by Letters Patent, is—

1. In a corn planter, the combination, with the vibrating lever which actuates the dropping slides, of a pivoted arm bearing a marker

and checker, the actuating rods l m, linked together and connected to a cross-piece on said lever, and a grooved cam in the clutching-hub C, substantially as described.

2. The combination of the articulating marker-arms, the markers J', the vibrating checkers K, the pulley-standards s on the corn-boxes, and the ropes or chains, all constructed and adapted to operate as described and shown.

3. The combination, in a corn planter, of an articulating line-marker, a checker, K, pivoted to its heel to vibrate at right angles to the line of draft, and means for vibrating said checker simultaneously with the dropping movements of the seed-slides e e, as shown and described.

In testimony whereof I affix my signature in presence of two witnesses.

JOSHUA A. SHAW.
